CLAIM

The ornamental design for a projector, as shown and described.

DESCRIPTION

FIG. 1 is a front view of a projector showing my new design;
FIG. 2 is a rear view thereof;
FIG. 3 is a left side view thereof;
FIG. 4 is a right side view thereof;
FIG. 5 is a top plan view thereof;
FIG. 6 is a bottom plan view thereof;
FIG. 7 is a perspective view thereof, and,
FIG. 8 is another perspective view thereof.
The dashed or broken lines shown in the drawings depict
portions of the projector in which the design is embodied
that form no part of the claimed design.

1 Claim, 8 Drawing Sheets
